UNITED STATES PATENT OFFICE

ERNST BREITLING, OF ESSEN, GERMANY, ASSIGNOR TO FRIED. KRUPP AKTIENGESELLSCHAFT, OF ESSEN-ON-THE-RUHR, GERMANY

LINE-ADJUSTING MECHANISM

Application filed February 26, 1929, Serial No. 342,882, and in Germany April 13, 1928.

The invention relates to mechanisms for adjusting the lines on vouchers to be introduced in the printing mechanism of a book-keeping machine or the like, in which mechanisms the table intended to receive the voucher is so moved in dependence upon a special setting mechanism that the line to be printed of the voucher is brought to coincidence with the printing line of the printing mechanism.

With known mechanisms of this type the table is moved by an external force acting upon it onto stops that are set by the setting mechanism, the number of these stops or, if a single adjustable stop is made use of, the number of its stop positions corresponding to the number of the lines of the voucher, so that, if the voucher comprises e. g. 39 lines, 39 keys are required.

According to the invention, the setting mechanism is subdivided decimally, so that the units, tens, hundreds etc. of the consecutive number of the lines of the voucher may be set separately.

Furthermore, according to the invention the table is moved onto the stop set not by an external force with the concurrence of springs, but by a differential mechanism of the tongs-closure type.

By these means therefore both the setting mechanism is simplified, because e. g. for 39 lines only 12 keys are required, and the motion of the voucher table onto the stop takes place with absolute security, even if a great resistance obstructs the motion of the table, e. g. by the introduced voucher crimping.

In order to allow of the invention to be more easily understood, a preferred embodiment of the subject-matter of same is illustrated by way of example in the accompanying drawings as applied to a book-keeping machine having a squarely shiftable voucher table. In these drawings—

Figure 1 is a top view of the mechanism,
Figure 2 is a corresponding side view,
Figure 3 is a section on line III—III of Figure 1,
Figure 4 is a section on line IV—IV of Figure 1 and shows the units key board,

Figure 5 is a section on line V—V of Figure 1 and shows the tens key board,

Figure 6 is a section through the units key board on line VI—VI of Figure 4,

Figure 7 is a lateral view showing the differential members of the units key board, and

Figure 8 is a section on line VIII—VIII of Figure 2.

Referring to Figures 1 to 3, 1 denotes the table the edges 2 of which are bent upward to secure the voucher put thereon. The table is guided on transverse bars 7, 8 mounted on the frame of the printing mechanism, by means of rollers 3, 4, Figure 3, and check rollers 5. A large rectangular aperture 9, Figure 1, provided in the table 1 enables the hammer (not shown) arranged opposite the printing drum 11, Figures 1 and 2, to effect the impression upon the voucher, which impression takes place from the corresponding set drum on the line 12, Figure 2.

The table 1 carries a rack 13, Figure 2, in mesh with a differential wheel 15 mounted on a carrier 14 and further in mesh with a rack 17 of a bar 16 shiftable guided on the frame of the mechanism. The carrier 14 is rigidly connected by a fish-plate 20 to a bar 18 likewise guided in the frame of the mechanism.

The bar 16 is set, in a manner to be described hereinafter, in dependence upon the keys 19, Figures 1 and 4, provided for the units of the line number, whilst carrier 14 is set in dependence upon the keys 21, Figures 1 and 5, provided for the tens of this number.

After the termination of this setting motion two locking arms 24, 25, Figure 2, are brought into mesh with locking teeth 28, 29 of the bars 16, 18, respectively. The locking arms 24, 25 are mounted on two pins 22, 23, fixed in the frame of the mechanism, and are both connected to a pitman 27 influenced from a cam disk 26. Due to this engagement the bars 16, 18 are exactly set and locked in set position. In order to damp blows occurring due to violent setting motion, the differential wheel 15 by which both the shifting motion of bar 16 and that of bar 18 is transmitted onto the table, is resiliently mounted on carrier 14. To this end carrier 14 is bifurcated,

Figures 1 and 8, and has oblong holes 32 wherein the journal 31 of wheel 15 rests and is normally held in contact with the right-hand wall of the holes 32 by a spring 33.

5 The bar 16, Figures 2 and 4, carries a rack 34 on its right-hand end with which rack is in mesh a pinion 36 mounted on a shaft 35 fixed in the frame 6 of the printing mechanism. This shaft further carries a pinion 37, 10 Figure 4, in mesh with a shiftably mounted rack bar 38, Figures 1, 2, and 4. The latter is in positive connection with a pinion 43 through the intermediary of a pinion 39, Figure 4, a tubular shaft 41 mounted in the 15 frame, and a pinion 42, the pinion 43 being fixed on a differential shaft 44 arranged below the units key row 19. Shaft 44 carries a series of lugs 45, Figures 6 and 7, that are distributed thereon along a helical line and 20 adapted to co-operate with the feet of the individual keys 19. Therefore, when after depression of a key 19, shaft 44 is rotated so far that the lug 45 allotted to the depressed key 19 comes into contact with the latter, this 25 rotation amounts to that number of angular units which corresponds to this key. Consequently also table 1 is shifted the same number of units through the intermediary of differential wheel 15, bar 16 and members 36, 30 35, 37, 38, 39, 41, 42, 43.

The described contact between the lugs 45 and the respective keys 19 is effected by an auxiliary differential member 46 mounted on shaft 44, Figures 6 and 7. This member is 35 formed by a sleeve which is cut away along a helical line and has stepped engaging faces 47. Member 46 is positively connected to a rack 53, Figures 2 and 4, by pinions 48, 49, Figure 4, a sleeve 51, and a pinion 52.

40 A shaft 54, Figures 1 and 2, has rigidly mounted on it swing arms 55 the free ends of which are bifurcated so as to form a slot 56 in which a block 57 is shiftable. This block carries a journal having mounted on it 45 a differential wheel 59 permanently in mesh with the racks 38 and 53.

After one of the keys 19 has been depressed, a swing motion toward the left, Figure 2, is imparted to the arms 55, the journal 58 assuming the position 58' and a total motion of ten units being transmitted to the racks 38, 53. Whilst the lugs 45, Figure 7, of the main differential member 44 in the position of rest are an angular distance away from the respective key feet which corresponds to the numeral of the key, the angular distance of the faces 47 of the auxiliary differential member 46 from the key feet in this position corresponds to the complementary value of the 55 numeral of the key. The total motion of ten units imparted to the racks 53, 38 thus is so distributed on them that the main differential member 44 and therewith the bar 16 and table 1 move by the value corresponding to the depressed key 19, whilst the auxiliary differ-

ential member 46 moves by the value which is complementary to the former. The motion of the two differential members takes place in opposite direction, Figure 6. At the end of the driving motion of the swing arms 55 the lugs 45, 47 abut from both sides on the foot of the depressed key. Any lag of differential member 44, as it may occur when actuated by an external force, in particular if resistances arise on the table e. g. by the voucher crimping, is thus impossible. 70

The keys 19 are equipped with lateral pins 61 by which they co-operate with a locking bar 62 that in known manner locks the keys in depressed position. The locking bar 61 has rigid on its forward end an arm 63 which as long as no key is depressed projects into the path of a stop 64 fast on shaft 44 and stops the latter in zero position. By depressing a key the locking bar 62 is shifted to the left, 80 Figure 4. The left-hand side walls 65 of its locking hooks are so arranged that bar 62 cannot be retired by its spring 66 to its extreme right hand position, if a key 19 is maintained in depressed position. In this position of bar 62 arm 63 is out of the path of stop 64, so that shaft 44 is free for the differential motion. 85

In a similar manner a main differential member formed by a shaft 67 and an auxiliary 90 differential member formed by a mutilated sleeve 68 are provided for the row of tens keys 21, Figure 5. Shaft 67 is positively connected by pinions 69, 70, 71 to bar 18 connected to the differential wheel carrier 14, 100 and is connected by a tubular shaft 72 fast on pinion 71, and by a pinion 73 to a rack 74 which corresponds to rack 38 of the units place. The auxiliary differential member 68 is in positive connection with a rack 79 through pinions 75, 76, a tubular 77, and a pinion 78; rack 79 corresponding to rack 53 of the units place. A differential wheel 81, Figure 1, likewise mounted on journal 58 is in mesh with the racks 74 and 79 and imparts 105 to them a total shifting motion of ten units, upon arms 55 rocking, whereby the stepped lugs of the two differential members 67, 68 are moved from both sides onto the foot of the depressed key. In the same manner as in the units place the key locking bar 82 is fitted with an arm 63 which locks the main differential member 67 in zero position as long as no key 21 is depressed. 110

The tens key board comprises three keys 120 10, 20, and 30, Figures 1 and 5; the lugs, co-operating with them, of the main differential member 67 are so arranged and the ratio of transmission from the latter to the differential wheel carrier 14, Figure 2, is so determined that the latter is moved 5, 10, or 15 units by depressing, respectively, key 10, 20, or 30. By the differential wheel 15 double the amount of the motion of carrier 14 is transmitted to the table 1, so that the latter 130

adjusts itself to the line 10, 20, or 30, upon respectively, key 10, 20, or 30 being depressed. Therefore, by depressing the respective units and tens keys the table 1 can be adjusted to 5 every one of the lines 1 to 39.

The described line adjusting mechanism is intended for a number of lines comprising at most two places. There is no hindrance, however, to design the mechanism for a number 10 comprising more than two places. To this end only the differential gear 13 to 16, Figure 2, had to be modified accordingly. For a number of three places, this could be made e. g. by not rigidly connecting rack 13 15 to table 1, but by means of a differential wheel the carrier of which is set by the hundreds key row to be provided for in addition.

The key rows for the line adjusting mechanism are annexed to the account number key 20 field, whereby much space is saved and the manipulation is simplified in comparison with mechanisms having transversely extending key rows. As to be seen from Figure 1, the account number keys 83 are arranged on 25 the left and the date keys 84 on the right beside the line keys 19, 21. The motion of the table thus takes place here normally to the direction of the key rows. This has been made possible by the corresponding arrangement 30 of the transmitting members.

The substance of the invention is not deviated from by providing in place of the table a stop on which abuts the voucher introduced.

35 I claim:—

1. A mechanism for adjusting the lines to be printed on a voucher to be introduced in a printing mechanism comprising a table adapted to receive a voucher, a setting mechanism for adjusting said table to the line to be printed, including a separate decimal setting mechanism for each decimal part of the line number whereby the decimal parts of the line number may be set separately.

45 2. A mechanism according to claim 1, including a differential connection between said table and said decimal setting mechanism, said connection including a differential gear, means for separately transmitting the setting of each of said decimal setting mechanisms to said differential gear, said differential gear being adapted to accumulate said settings, and means for transmitting said accumulated setting to said table.

55 3. A mechanism for adjusting the lines to be printed on a voucher to be introduced in a printing mechanism, comprising a table adapted to receive a voucher, a setting mechanism including a separate decimal setting mechanism for each decimal part of the line member, a rack on said table, a second rack connected to one of said decimal setting mechanisms, a differential wheel in mesh with each 60 of said racks, a carrier for said differential

wheel, said carrier being connected to another of said decimal setting mechanisms.

4. A mechanism according to claim 3, in which said carrier is provided with two parallel arms, a slot in each arm, said differential wheel being mounted on a journal, said journal being secured in said slots, and a spring interposed between said carrier and said journal tending to hold said journal against one end of said slots.

70 5. A mechanism according to claim 3, which includes said carrier and the said second rack being each provided with rest teeth, a locking member adapted to engage the rest teeth on said carrier, a second locking member adapted to engage with the rest teeth on said second rack, and a common pitman for actuating said locking members.

75 6. A line adjusting mechanism comprising a voucher table, means for moving said table to a predetermined position including a selectively set stop, a differential mechanism consisting of two actuating members each cooperating with said stop, means for moving each of said actuating members a distance equal to the complement of the distance moved by the other of said actuating members, said means including a differential member.

80 7. A line adjusting mechanism comprising a voucher table, means for moving said table to a predetermined position including a row of keys, a foot on each key of said row, a shaft extending below said key row, helically distributed lugs on said shaft cooperating with one side of the respective key feet, a mutilated sleeve arranged concentrically on said shaft, helically distributed faces on said sleeve cooperating with the other side of said respective key feet, means for moving said sleeve and shaft each a distance equal to the complement of the distance moved by the other, including a rack connected to said shaft and also to said table, a second rack connected to said sleeve, a differential gear wheel in mesh with each of both of said racks, means for imparting to said differential wheel a predetermined longitudinal motion.

85 8. A mechanism according to claim 1, including account key rows, additional key rows for said setting mechanism, said additional key rows being arranged in the same direction as said account key rows, means connecting said setting mechanism and said table for moving said table transversely of the key rows.

90 9. A mechanism according to claim 1, including account key rows, additional key rows for said setting mechanism, said additional key rows being arranged within the field of said account key rows and also arranged in the same direction as said account key rows, and means connecting said setting mechanism and said table for moving said table transversely of the key rows.

10 10. A mechanism according to claim 3,

provided with a key row for each decimal setting mechanism, the ratio of movement of said carrier to said first named rack being 1:2 and the ratio of the movement of said carrier between adjacent keys of the tens mechanism to the movement of said second rack between adjacent keys of the unit mechanism being 5:1.

5. 11. A mechanism according to claim 6, in which said stop consists of one of a plurality of keys adapted to be selectively depressed, said mechanism also including a locking bar for locking said keys in their depressed position, an arm on said locking bar, a stop on 10 said differential mechanism, said arm in the normal position of the locking bar projecting into the path of said last named stop whereby said differential mechanism is locked in its zero position, and means connected with 15 each of said keys for moving said locking bar from its normal position upon the depression of any of said keys.
- 20 11. A mechanism according to claim 6, in which said stop consists of one of a plurality of keys adapted to be selectively depressed, said mechanism also including a locking bar for locking said keys in their depressed position, an arm on said locking bar, a stop on 25 said differential mechanism, said arm in the normal position of the locking bar projecting into the path of said last named stop whereby said differential mechanism is locked in its zero position, and means connected with each of said keys for moving said locking bar from its normal position upon the depression of any of said keys.

The foregoing specification signed at Cologne, Germany, this 6th day of February, 25 1929.

ERNST BREITLING.
